US00D487276S

(12) **United States Design Patent** (10) Patent No.: **US D487,276 S**
Cobigo (45) Date of Patent: ** Mar. 2, 2004

(54) **SOUND TRANSMITTING DEVICE**

(75) Inventor: **Stephanie Cobigo**, Eindhoven (NL)

(73) Assignee: **Koninklijke Philips Electronics N.V.**,
Eindhoven (NL)

(**) Term: **14 Years**

(21) Appl. No.: **29/177,608**

(22) Filed: **Mar. 12, 2003**

(30) **Foreign Application Priority Data**

Oct. 2, 2002 (WO) DMA/055 858

(51) LOC (7) Cl. **14-03**

(52) U.S. Cl. **D14/496**; D10/104

(57) **CLAIM**

The ornamental design for a sound transmitting device, as shown.

DESCRIPTION

FIG. 1 is a perspective view showing my design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 4 Drawing Sheets
